Carl J. Anderson, Lakewood, Ohio, assignor to
The Baker-Raulang Company, Cleveland,
Ohio, a corporation of Ohio

Application August 8, 1938, Serial No. 79,187

Term of patent 7 years

To all whom it may concern:

Be it known that I, Carl J. Anderson, a citizen of the United States, residing at Lakewood, in the county of Cuyahoga and State of Ohio, have invented a new, original, and ornamental Design for a Vehicle, of which the following is a specification, reference being had to the accompanying drawings, forming part thereof.

Fig. 1 is a side elevational view of a vehicle showing my new design;

Fig. 2 is an elevational front view thereof;

Fig. 3 is a side perspective view; and

Fig. 4 is rear elevational view.

I claim:

The ornamental design for a vehicle, as shown.

CARL J. ANDERSON.
